(57) **CLAIM**

We claim the ornamental design for a self-service terminal, as shown and described.

DESCRIPTION

FIG. 1 is a front perspective view of a self-service terminal of the present invention;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a bottom-front perspective view thereof;

FIG. 10 is a cross-sectional view taken along the line 10-10 of FIG. 3 thereof; and,

FIG. 11 is a cross-sectional view taken along the line 11-11 of FIG. 3 thereof.

The broken line showing of self-service terminal is included for the purpose of illustrating environment and forms no part of the claimed design.
